US0D1106845S

(12) **United States Design Patent** (10) **Patent No.:** **US D1,106,845 S**
(45) **Date of Patent:** **** Dec. 23, 2025**

(54) **GLOBAL POSITIONING DEVICE**

(71) Applicant: **Tenways Technovation Europe B.V.**,
Amsterdam (NL)

(72) Inventor: **He Huang**, Amsterdam (NL)

(73) Assignee: **Tenways Technovation Europe B.V.**,
Amsterdam (NL)

(**) Term: **15 Years**

(21) Appl. No.: **29/973,856**

(22) Filed: **Nov. 19, 2024**

Related U.S. Application Data

(62) Division of application No. 35/519,578, filed on Dec. 15, 2023 (U.S. filing date under 35 U.S.C. 384), and having an international filing date of Dec. 15, 2023, now Pat. No. Des. 1,071,757.

CLAIM

The ornamental design for a global positioning device as shown and described.

DESCRIPTION

FIG. 1 is a top, front and left side perspective view of a global positioning device embodying my new design;
FIG. 2 is a top, rear and right side perspective view thereof;
FIG. 3 is a top plan view thereof;
FIG. 4 is a left side elevational view thereof;
FIG. 5 is a front side elevational view thereof; and,
FIG. 6 is a back side elevational view thereof.
The broken lines shown are included for the purpose of illustrating portions of the global positioning device that form no part of the claimed design.

1 Claim, 6 Drawing Sheets
